The ornamental design for an electrical housing, as shown and described.

DESCRIPTION

FIG. 1 is a perspective view of an electrical housing showing a new design;

FIG. 2 is a front view of FIG. 1;

FIG. 3 is a rear view of FIG. 1;

FIG. 4 is a LEFT SIDE view of FIG. 1;

FIG. 5 is a RIGHT SIDE view of FIG. 1;

FIG. 6 is a top view of FIG. 1; and,

FIG. 7 is a bottom view of FIG. 1.

The broken lines in the drawings depict portions of the electrical housing that form no part of the claimed design.
